PANELLING MATERIAL

Colman Zola, 58 Tamarack Way, Pleasantville, N.Y.

Filed May 7, 1962, Ser. No. 69,999

Term of patent 3½ years

(Cl. D13—1)

FIG. 1

FIG. 2

FIG. 1 is a front view of a panelling material showing my new design; it is to be understood that the design is repeated both horizontally and vertically the length and width of the panelling material; and

FIG. 2 is a perspective view thereof.

The undisclosed side of the panelling material is plain.

I claim:

The ornamental design for a panelling material, as shown and described.
